CLOSURE

Hollie C. Romaine, Saginaw, Mich.

Application May 24, 1933, Serial No. 672,525

6 Claims. (Cl. 20—52.6)

This invention relates to a weather strip or like device for sealing the crack around a movable closure such as a window or door, etc. More particularly, the invention relates to a sealing strip which is adapted by the final closing of the closure to be forced against the closure and its casing adjacent the crack, so as to seal the space between them.

Prior to this invention, weather strips generally have been of spring metal or compressible packing material adapted to press resiliently against the closure member. Such weather strips, however, if made of resilient metal, frequently become bent, or fail to adjust themselves to small irregularities in the surface against which they are pressed, so that they do not form a tight seal, whereas compressible packing materials such as rubber, felt, etc., soon become hardened, packed or worn away to such an extent that they fail to function satisfactorily. All of these, furthermore, by rubbing against the window during its operation, tend to make the opening and closing of the window more difficult, and frequently to produce objectionable wear on the window frame.

It is an object of my present invention to provide a weather or sealing strip which is forced laterally into sealing position only when the window, etc., is finally closed, and which will be free from the parts against which it is pressed as soon as the window, etc., is substantially opened. Another object of the invention is to provide a weather strip, etc., which will hold the windows, etc., against rattling in the wind. Still another object of the invention is to provide a means which becomes automatically effective as a brake when the window is closed violently so as to prevent substantial rebound from the sill, and to assure tight closing of the window, even though it may not have been locked. Other objects and advantages of the invention will appear from the following specification and the accompanying drawing.

Stated briefly, my invention contemplates the provision of a strip slidably mounted adjacent the crack between the closure and its casing, and operatively connected to the closure during a very short distance during the final closing movement of the closure, etc., so that the weather strip will be driven thereby into sealing relation between the closure and its casing, and advantageously also into a wedging relation therebetween. By such wedging the crack at one side may be sealed by the weather strip itself, and at the other side may be substantially closed by wedging the window, etc., against its casing.

I am aware that weather strips have been constructed prior to my invention in which a strip mounted on a door, or other closure, has been moved outwardly by the final closing movement of the door, so as to extend across any large crack which may be existing, e. g., beneath the door to accommodate rugs, etc., or at the side in the case of grain cars or bins. In every case, however, such strips have been merely to extend the door across a relatively large crack, and have not been effective as sealing means, since the crack between this extension strip and the door has necessarily remained just as important an avenue of leakage as the cracks which ordinarily exist between a door or window and its casing.

In distinction to such prior art closure strips, the sealing strip of the present invention constitutes a means adapted to be pressed against, or wedged into, the crack which it is desired to close, and as such constitutes a complete departure in conception from any weather strip known prior to my invention.

In the drawing, I have shown in Fig. 1 a fragmentary elevation of a double hung window with a weather strip made according to my invention applied to the inside thereof;

Fig. 2 is a vertical section taken on line 2—2 of Fig. 1;

Fig. 3 is a horizontal section taken on line 3—3 of Fig. 1;

Fig. 4 is a vertical sectional detail taken on line 4—4 of Fig. 1;

Figs. 5, 6 and 7 are cross-sectional views of alternative types of weather strip which may be used according to the present invention;

Figs. 8 and 9 are cross-sections similar to Fig. 3, showing alternative positioning of the weather strip; and

Fig. 10 is a vertical section taken on line 10—10 of Fig. 9.

In the embodiment shown in Fig. 1 of the drawing, the weather strip has been shown on the inside of the window. The placing of the strip is a matter of convenience, and is not essential to the invention. When applied to a window already hung, it will ordinarily be applied either to the inside or the outside of the frame, but it may also be built in, for example, as illustrated in Figs. 8 and 9, and as will be more fully described below.

The strip 10 itself preferably comprises, e. g., as shown in Figs. 5 to 7, a narrow metal strip 11 of sufficient rigidity to exert a lateral edge-wise pressure and a resilient tip 12 which may be of spring metal, as shown in Fig. 5, but prefer-

ably is of resilient material such as rubber or other flexible molded material, or if the strip 11 is suitably designed, may be of felt, leather, woven fabric, etc. It is not essential, however, 5 that the tip 12 should be resilient, and even if the tip 12 is rigid, it will, by pressure against or wedging into the crack, constitute a more complete and satisfactory seal than do other types of weather strips. The strip 10 is mounted on 10 the window frame 14 or in the casing 15, so that its flexible tip 12 will, with a slight lateral movement, be projected into or against the crack between the window frame and its casing, and by movement in the opposite direction may be 15 withdrawn therefrom. Means is provided for effecting the lateral movement of the strip from the final movement of the window. In the example illustrated, this means comprises cam slots 16 and screws 17, the screws in this case 20 also serving as the means for attaching the strip to the window frame.

It will be observed that in the embodiment illustrated in Fig. 1, the cam slots 16 are not at a uniform angle to the direction of movement 25 of the window, but, on the contrary, form relatively steep cams for a short distance adjacent the closing of the window, and then flatten off so as to give a greater mechanical advantage to the window in forcing home the sealing strip. 30 This design of the cam slot also provides for stopping the window substantially as it strikes its fully closed position, and substantially preventing rebound which would leave the window partially open. In some cases, it will be more 35 advantageous to shape the slot so that after the first steep portion it changes direction and is cut parallel with the edge of the strip for about $\frac{3}{8}$ or $\frac{1}{2}$ inch. At the bottom of the slot there may be a short additional slope to drive the strip tighter 40 against the crack. Thus the strip will be held in substantially full sealing relation throughout the last half or $\frac{3}{8}$ inch of the movement, and if the window should not be closed quite tightly, the crack will, nevertheless, be substantially sealed.

45 A spring or springs 20 may be provided to pull the strip into its released position as soon as the window is raised and hold it constantly in said released position. On the lower sash of a double hung window, this spring is not ordinarily necessary, because the weight of the strip itself will 50 hold it down in the released position. On the upper sash, however, the weight of the strip would tend to hold it in closed position, and it is therefore important to provide some means for holding the strip away from the casing, so that 55 it will not grab into sealing position by its own friction against the casing before the window is closed.

60 The bottom of the strip in the example illustrated is turned over, as at 21, to form a foot which, in the closing of the window, strikes against the striker plate 22, and upon opening the window, strikes against a pin 23. When the window is closed, the foot 21 strikes the plate 22 65 just before the final closing of the window is completed, and thereby drives the strip upwardly and by means of the cam slots 16 and the cam screws 17 forces the strip laterally into sealing relation. At the same time, the foot 21 is moved laterally beneath the pin 23. Upon opening the window, this foot will catch upon the pin 23, and will be held until the strip has been moved 70 away from the casing, whereupon the foot 21 will be withdrawn from under the pin 23, and the

window may be opened without interference of any kind from the sealing strip.

The striker plate 22, of course, is not essential, 5 since the foot 21 may be allowed to strike directly upon the window sill. The use of the striker plate, however, prevents any disfiguring of the window sill, and at the same time affords a convenient means for adjustment. If, for example, the parts should become worn so that the strip no longer 10 fully seals the crack it is only necessary to remove the plate 22 and place a shim of paper or cardboard beneath it, whereupon the strip will be driven further towards the crack. If desired, the 15 striker member may be an adjustable screw instead of a plate as shown or other means may be provided. It is also desirable, in some cases, to provide a manually movable member having both 20 striker plate 22 and pin 23 secured thereto, so that upon opening of the window, these members may be first manually moved so as to release the 25 sealing strip before the window is raised. Adjustment may also be obtained in other ways, as, for example, by the use of eccentric collars 25 on the screw 17.

In Figs. 8 to 10, I have illustrated, by way of 25 example, the building of the strips into the window frame or casing, so that they are hidden from view. The operation of the strip illustrated in Fig. 8 may be precisely the same as that already 30 described in connection with the other figures, the triangular slot 30 being provided in the edge of the window frame to accommodate the strip, and the cam screws 17, and other parts. Although in 35 many cases, for the sake of appearance or convenience, it may be preferable to mount the sealing strips on the inside of the window, it is more 40 advantageous, whenever possible, to place the strips, e. g., as shown in Fig. 8, as near as possible to the outer edge of the window, and particularly to place it so that it is wedged between the window and the piece which is adjacent the outer 45 edge of the window, so that drafts which are stopped from entering between the window and its casing by the sealing strip will not be merely diverted through some other crack into the wall from which they may escape at some other point. Of course, even in this case there is some advantage because the amount of wind entering by such circuitous route would be considerably less than would pass directly through the crack which is 50 closed by the sealing strip. But a construction such as that illustrated in Fig. 8 will substantially 55 entirely prevent the entrance of wind around the window. In Figs. 9 and 10, the strip is shown as being mounted in the window casing instead of on the window frame, and accordingly it is necessary 60 to provide a connection such as that shown at 31 between the window frame and the strip, just as in the other embodiments illustrated the connection 65 21-22 is provided between the strip and the casing or sill. In the same way, a catch 32 should be provided to draw the strip into the released position when the window is opened. Of course, 70 these suggestions are intended merely by way of example to illustrate the principle of the invention, and to demonstrate that it is not limited to any particular embodiment. Numerous other ways of constructing and applying the sealing strip may be chosen by those skilled in the art, and it is to be understood that the invention is not 75 limited to the particular embodiments and modifications thereof described in this application.

What I claim is:

1. A sealing device for a closure, comprising a strip adapted to be forced against adjacent parts 75

of the closure and its casing to seal a crack therebetween, and means adapted to move said strip towards said crack and press it throughout its length against the closure and its casing and over 5 said crack.

2. A sealing device as defined in claim 1, in which the strip is generally wedge-shaped, so as to be forced into the crack between the closure and its casing.

10 3. In combination with a sliding window casing, a strip mounted adjacent a crack between the window and casing having a resilient edge adapted to seal said crack when forced into it, said strip having cam slots therein, means in said cam slots

15 for slidably securing said strip to the closure, whereby to convert longitudinal movement of the strip into a lateral movement toward and away from said crack, an adjustable striker member adapted to engage the strip just before the final

20 closure, whereby to cause said final movement of the closure to move said strip relative to the securing means and drive its edge against the crack, and means adapted to engage the strip while it is close to the striker member and close to the casing,

25 whereby to hold the strip during the initial opening of the closure until the movement of the securing means in the cam slots results in withdrawing the strip away from the casing and from said engaging means.

30 4. A device as defined in claim 1, in which the means adapted to move the frame member toward

the crack includes fixed and movable cam members, compressing cam slots, and bearing members 5 slideable relative thereto, and means adapted to be engaged with one of said cam members upon the final closing movement of the closure so as to apply a part of the force of said final movement to relative movement of said cam members, whereby to move the frame member towards its crack, and the cam slots are designed so that the strip is pressed against the closure a short but 10 substantial distance before the closure is completely closed, whereby the strip serves as a brake to absorb momentum of the closure and to prevent rebound after the window is closed.

5. In combination with a movable closure and 15 casing therefor, a sealing strip inset between the closure and its casing, and means for adjusting said sealing strip so as to crowd it into a narrow space between closure and casing so as substantially completely to fill said space.

20 6. In combination with a movable closure and a casing therefor fabricated of a plurality of pieces, a sealing strip adapted to fit against the closure and a piece of the casing which is adjacent the outer edge of the closure and to close a 25 crack between them, and means for forcing said strip against the closure and casing when the closure is shut and for retracting it therefrom when the closure is opened.

30 HOLLIE C. ROMAINE.
